UNITED STATES PATENT OFFICE

142,904

DESIGN FOR A REFRIGERATOR SHELF

Ormond H. Paddock, Rossford, Ohio, assignor to Libbey-Owens-Ford Glass Company, Toledo,
Ohio

Application September 14, 1944, Serial No. 115,297

Term of patent 14 years

(Cl. D33—3)

To all whom it may concern:

Be it known that I, Ormond H. Paddock, a citizen of the United States, residing at Rossford, in the county of Wood and State of Ohio, have invented a new, original, and ornamental Design for a Refrigerator Shelf, of which the following is a specification, reference being had to the accompanying drawing, forming part thereof.

Fig. 1 is a side perspective view of a refrigerator shelf showing my new design; and

Fig. 2 is a section taken substantially on the line 2—2 in Fig. 1.

I claim:

The ornamental design for a refrigerator shelf, substantially as shown.

ORMOND H. PADDOCK.
